Primary Examiner — T Chase Nelson*Assistant Examiner* — Kelly L Gross(74) *Attorney, Agent, or Firm* — Jacob M. Ward; Ward Law Office LLC(57) **CLAIM**

The ornamental design for a scrotal edema pressure redistribution device, as shown and described.

DESCRIPTION

FIG. 1 is a top perspective view of a scrotal edema pressure redistribution device;

FIG. 2 is a bottom perspective view of the scrotal edema pressure redistribution device shown in FIG. 1;

FIG. 3 is a right side elevational view thereof;

FIG. 4 is a rear side elevational view thereof;

FIG. 5 is a front side elevational view thereof;

FIG. 6 is a top plan view thereof; and,

FIG. 7 is a bottom plan view thereof.

A left side elevational view is not shown because it is a mirror image to the right side elevational view shown in FIG. 3.
